UNITED STATES PATENT OFFICE.

SAMUEL G. GRIFFITHS, OF HUNTINGTON, INDIANA.

REENFORCING TRUSS OR FRAME.

Application filed July 8, 1925. Serial No. 42,250.

This invention relates to new and useful improvements in concrete reenforcing trusses or frames.

The primary object of my invention is to provide a concrete reenforcing truss or frame consisting of a plurality of independent parts or units which may be easily and readily assembled and locked into a rigid compact assemblage.

With the foregoing and other objects in view that will appear as the nature of my invention is better understood, the same consists in the novel features of construction, combination and arrangement of parts illustrated in the accompanying drawings and more particularly pointed out in the appended claims.

In the accompanying drawings, which are for illustrative purposes only and are therefore not drawn to scale:—

Fig. 1 is a top plan.

Fig. 2 is a side elevation.

Fig. 3 is a plan of the sections of the main frame with the connecting sleeves therefor in horizontal section.

Fig. 4 is an end view.

Fig. 5 is a fragmental perspective of one end of the truss, and

Fig. 6 is a transverse section with the central spacing element shown in elevation.

Referring to the drawings for a more particular description of my invention and in which drawings like parts are designated by like reference characters throughout the several views, my concrete re-enforcing truss comprises, first, a substantially rectangular frame A consisting of the longitudinal side members 1, preferably in the form of cylindrical steel rods, formed at opposite ends with the inwardly and right angularly bent portions 2 connected together by the cylindrical sleeves 3 which co-act with the aforesaid end portions in forming the end members of said rectangular frame.

A series of three or more parallel laterally spaced re-enforcing members 4 and 5, preferably in the form of cylindrical steel rods, extend lengthwise of the frame A, as shown.

The central rod 4 is perfectly straight throughout its entire length except at its ends, which are bent downwardly at right angles, as at 6, to form the lugs 7 adapted to hook over the sleeves 3. The outer rods

5 comprise the central straight portions 7 and the raised outer portions 8 which are

gradually inclined downwardly and outwardly and terminate at their opposite ends in the downwardly and outwardly bent lugs 9 which engage or hook under the sleeves 60 3 aforesaid. With the parts in this position, the cross rods 10 are inserted between the side members of the frame A and the central re-enforcing member 4 and the raised end portions of the outer re-enforcing members 5. This firmly secures or locks the several component parts together in one compact rigid assembly.

A central transverse spacing element B is employed to hold the side member 1 of the frame A and the rods 4 and 5 in proper spaced relation. This element is in the form of a single continuous wire bent centrally upon itself with its ends 11 and 12 bent around one side member of the frame A and corrugated or bent, as at 13 and 14, to receive the other side member of the frame and the rods 4 and 5, respectively.

My device may be used for re-enforcing concrete bridges, floors, or cement or concrete structures of any character where the same may be used to advantage.

From the foregoing description, taken in connection with the drawings, it is thought that the construction, operation and advantages of my invention will be readily understood without requiring a more extended explanation.

Having described my invention, what I claim as new and desire to secure by Letters 90 Patent is:—

1. A reenforcing truss including a frame having side and end portions, a plurality of rods extending longitudinally of the frame between the side portions thereof, the ends 95 of certain of the rods being bent to engage over one face of the end portions of the frame and the ends of the other rod being bent to engage over the opposite face of the end portions, and transversely extending 100 rods engageable with the side portions of the frame and with opposite faces of alternate longitudinally extending rods.

2. A reenforcing truss including a rectangular frame formed of sections, means for detachably connecting the ends of the sections, and rods extending longitudinally of the frame, intermediate the sides thereof, and engageable with the ends.

3. A reenforcing truss including a rectangular frame formed of sections detachably connected at their ends by telescoping

sleeves, and rods extending longitudinally of the frame and engageable with the ends thereof.

4. A reenforcing truss including a frame formed of longitudinally extending portions having their ends bent inwardly and sleeves into which the inwardly extending end portions are received for connecting the sections, and rods extending longitudinally of the frame and engageable with the end portions thereof.

5. A reenforcing truss including a frame formed of longitudinally extending portions having their ends bent inwardly and sleeves into which the inwardly extending end portions are received for connecting the sections, and a plurality of rods extending longitudinally of the frame with the ends of alternate rods bent to engage on opposite sides of the connecting sleeve.

6. A reenforcing truss including a frame formed of longitudinally extending portions

having their ends bent inwardly and sleeves into which the inwardly extending end portions are received for connecting the sections, a plurality of rods extending longitudinally of the frame with the ends of alternate rods bent to engage on opposite sides of the connecting sleeve, and a transversely extending rod engageable with the frame and the longitudinally extending rods.

7. A reenforcing truss including a frame, having side and end portions, a rod extending longitudinally of the frame, centrally thereof, and engageable with the end portions thereof, and rods extending longitudinally of the frame on opposite sides of the first mentioned rod with their ends engageable with the ends of the frame, said last mentioned rods having raised portions adjacent the end portions of the frame.

In testimony whereof he affixes his signature.

SAMUEL G. GRIFFITHS.
